United States Patent Office

Des. 210,689
Patented Apr. 2, 1968

210,689

BATHROOM SCALE

Nolan K. Rhoades, Beloit, Wis., assignor to The Brearley Company, Rockford, Ill., a corporation of Illinois

Filed Apr. 6, 1967, Ser. No. 6,555

Term of patent 14 years

(Cl. D52—10)

FIG. 1

FIG. 2

FIG. 3

FIG. 4

FIG. 5

FIG. 6

FIG. 1 is a perspective view of a bathroom scale showing my new design;

FIG. 2 is a top view;

FIG. 3 is a front elevational view;

FIG. 4 is a side elevational view as seen from the right of FIG. 3;

FIG. 5 is a rear elevational view; and

FIG. 6 is a bottom view.

I claim:

The ornamental design for a bathroom scale, substantially as shown.
